ALEXANDER STANOWSKY, OF ROTTERDAM, NETHERLANDS.

METHOD AND APPARATUS FOR CASTING METAL.

1,273,418.

Specification of Letters Patent. Patented July 23, 1918.

Application filed January 24, 1918. Serial No. 213,552.

To all whom it may concern:

Be it known that I, ALEXANDER STANOWSKY, residing at Rotterdam, the Netherlands, have invented certain new and useful Improvements in Methods and Apparatus for Casting Metal, of which the following is a specification.

This invention relates to a method and to an apparatus for casting metal such as is 10 extensively used by dentists for casting gold plates for artificial teeth, but which may also be employed for other purposes. The said apparatus comprises a flask in which the model or pattern formed of wax or the 15 like may be placed in a pad of refractory and absorbent material which in its original state is plastic but which hardens on being heated, the said model being in communication through a narrow passage with a crucible located within the muffle and preferably formed by a depression at the top of the pad. This pad, after the pattern is burned out constitutes the mold. When the flask is 20 heated and the model melted, the wax or 25 the gases generated disperse through the refractory pad, whereby in the latter a cavity is left which exactly corresponds to the outline of the casting to be made. At the same time the required quantity of gold or other 30 metal is brought to a molten state, after which the flask is closed and a gas under high pressure, for instance carbonic acid, is introduced thereinto, by which the molten metal is pressed through the narrow 35 passage into the cavity, which thereby is entirely filled up.

Apparatus of this class as hitherto in use are rather expensive and not easily handled, as their operation depends upon a big cylinder containing the gas under high pressure or upon an air pump and the necessary connection pipes, which are liable to leakage and in many other respects cause considerable trouble. According to the present invention this disadvantageous feature is obviated in a simple manner by the gas under pressure being let into the flask from a capsule whose wall on being pressed against the lid of the flask is punctured by a piercer 45 provided with a passage and placed in or on the flask, in such a manner, that an open

connection between the capsule and the interior of the flask is obtained.

The annexed drawing illustrates some embodiments of an apparatus for carrying out 55 the said method. In this drawing:—

Figure 1 is an elevation, partly a section, of an apparatus embodying the invention,

Fig. 2 a section of the upper part of the flask and of its lid with a capsule, placed on 60 same, whereas;

Figs. 3 and 4 illustrate sections of two different forms of the piercer for use in the lid.

In Fig. 1, 1 is the flask, 2 the refractory 65 and absorbent pad therein (forming the mold), 3 is the model placed in the said pad, 4 is the metal, *e. g.*, gold, placed in a depression of the pad. The lid 5 is secured to a lever 6 which at 7 is pivoted to a support 70. 8. A lever 9, which by means of a rod 10 and wing nut 11 is adapted to be fixed to the lid, is pivoted at 12 to the arm 13 of the lever 6, and has for its purpose to forcibly press the capsule 14, which may be filled 75 with liquid carbonic acid, on the lid 5, a rubber stuffing ring 15 serving for securing a tight connection.

According to Fig. 2 the lid 5 is provided on its top with a collar 16, inclosing a chamber whose bottom 17 has a central aperture for the passage of the piercer 18, which is provided with a shoulder 19. The piercer 18 is formed with a passage which constitutes the required connection between 85 the space 20 in the covered flask (*i. e.* the entire space within the assembled flask and lid), and the chamber inclosed by the collar 16 and the bottom wall 17. In the embodiment shown in Fig. 3 the said passage is 90 simply formed by a longitudinal saw-notch 21 extending from the top to a small distance from the bottom end through about half the thickness of the piercer. The piercer as shown in Fig. 4 is provided with a longitudinal bore hole 22 which, after the piercer has been placed in the proper position, is in connection with the muffle space 20 through a transverse passage 23.

A baffle plate 24 is secured to the bottom 100 end of the piercer 18 by means of a screw connection or in some other manner, a cer-

tain space being left between the upper face of this plate and the bottom face of the wall 17, whereas the periphery of the plate 24 extends to quite near the inner wall of 5 the lid.

The operation of the apparatus is as follows:—

After the model or pattern inclosed by the refractory pad in the flask is melted, 10 the wax absorbed, and the gold brought to a molten state, a capsule 14 containing carbonic acid or the like and closed at its bottom by a thin metal plate 25, is placed between the suitably formed lever 9 and the 15 lid 5, after a rubber washer or stuffing ring 15 has been arranged around the neck of the capsule. If now the lever 9 is forcibly pressed down, the ring 15 is gripped between the capsule 14 and the upper face of the collar 16, and the piercer 18 punctures the 20 plate 25 of the capsule, so that the carbonic acid in the capsule is free to flow through the passages 21, or 22 and 23, into the chamber formed between the baffle plate 24 and the bottom face of 17. From this chamber 25 it flows around the edge of the baffle plate 24 into the flask space 20 where it brings about the required pressure to force the gold through the passage 26 into the cavity formed in the pad. The excess of carbonic 30 acid is blown off through a hole 27 in the bottom of the flask and through an opening 28 in the base plate.

It will thus be seen that the flask 1 and 35 the lid 5, taken together form a container, and when the capsule 14 is in place, such capsule forms a hermetic closure for such container. The bottom, or thin part 25 of said capsule initially forms the closure to 40 the perforation in the lid 5, whereas, when the capsule 14 is pressed downwardly against the piercer 18, this thin bottom of the capsule is pierced and the gas in the capsule enters the container. After the bottom of 45 the capsule is pierced, the upper part of the capsule forms the closure for the perforation in the lid (of course in combination with the packing ring 15).

The baffle plate 24 has for its object to 50 prevent the carbonic acid flowing out of the capsule from blowing away the molten gold centrally below it.

The structure and location of the baffle plate 24, may be varied considerably, so long 55 as it is so located and constructed as to perform the function just stated. Said baffle plate can be secured to the piercer 18, as shown, or held in place in any other suitable manner.

60 What I claim as my invention is:

1. A metal-casing method of that type in which the molten metal is forced by gas under pressure into a mold located within a

flask provided with a perforated lid, such method comprising the successive steps of 65 closing the perforation in the lid by means including a capsule of gas under high pressure, and thereafter puncturing such capsule at that point thereof at which it initially serves to form the closure of the said perforation, whereby the contents of the capsule are admitted through the said perforation into the lid and flask.

2. A metal-casting method of that type in which the molten metal is forced by gas 75 under pressure into a mold located within a flask provided with a perforated lid, such method comprising the successive steps of closing the perforation in the lid by means including a capsule of gas under high pres- 80 sure, and thereafter puncturing such cap- 85 sule at that point thereof at which it ini- 90 tially serves to form the closure of the said perforation, whereby the contents of the capsule are admitted through the said per- 95 foration into the lid and flask and deflecting the high pressure gas current sufficiently to prevent the same from directly striking the molten metal, whereby the pressure is applied only indirectly on such molten metal. 100

3. In combination, in a metal casting de- 105 vice, a flask containing a mold, a perforated lid for such flask, an outwardly extending collar surrounding the perforation in such lid, such collar forming a chamber, a piercer 110 located within such chamber and being pro- 115 vided with a longitudinal passage, the bot- 120 tom of said piercer being located in the per- 125 foration in said lid, a baffle plate located within the inclosure formed by the flask and its lid, and being situated between the said perforation and the mold, and adapted to deflect the gas under pressure flowing into such inclosure, in such a way that the strong gas current does not strike the molten metal 130 located on the mold.

4. In a metal casting device, the combination of a flask containing a mold, a lid for said flask, such lid being provided with a hole, a piercer carried by said lid in prox- 135 imity to said hole, a compressed gas capsule adapted to completely cover said hole and to form a pressure-tight closure therefor, means for pressing such capsule against such piercer, while maintaining the said capsule 140 in position to form a pressure tight closure for such hole, a passage for allowing the compressed gas from said capsule to enter the said flask, and means for deflecting and diffusing the gas current, whereby the gas 145 pressure only, and not the current, comes into direct contact with the metal in the mold.

5. In the art of casting metal in a mold located within a pressure-tight container, 150 the improvement which comprises position-

ing a capsule containing gas under high pressure, where its interior, when the wall of such capsule is punctured, will be in communication with the interior of such container containing such mold and containing molten metal in communication with such mold, and then puncturing the wall of such capsule, whereby its high pressure gas contents are allowed to flow into such con-

tainer, to increase the gas pressure existing 10 therein.

In testimony whereof I have affixed my signature in presence of two witnesses.

ALEXANDER STANOWSKY.
